UNITED STATES PATENT OFFICE.

HENRY M. SHEER AND SANFORD C. PITNEY, OF QUINCY, ILLINOIS.

BOX-FASTENER.

SPECIFICATION forming part of Letters Patent No. 593,615, dated November 16, 1897.

Application filed January 4, 1897. Serial No. 617,965. (No model.)

To all whom it may concern:

Be it known that we, HENRY M. SHEER and SANFORD C. PITNEY, citizens of the United States, residing at Quincy, in the county of Adams and State of Illinois, have invented certain new and useful Improvements in Box-Lid Fasteners; and we do declare the following to be a full, clear, and exact description of the invention, such as will enable others skilled in the art to which it appertains to make and use the same, reference being had to the accompanying drawings, and to the figures of reference marked thereon, which form a part of this specification.

15 Heretofore it has been common to provide box-lids with a fastening device consisting of a pair of rods movable endwise in opposite directions to engage the opposite walls of the box-body, the inner ends of the rods being attached to the opposite ends of a pivoted lever in such a manner that when the bar is turned to the right or left it will cause the ends to move endwise and alternately engage and disengage the box.

25 The object of our invention is to improve upon devices of this character whereby our device will be more cheap, convenient, and desirable in both manufacture and use.

To this end our invention consists in the 30 peculiar features and combinations of parts more fully described hereinafter and pointed out in the claims.

In the accompanying drawings, Figure 1 represents a top view of our device as applied 35 to the cover of an ordinary box, the parts being shown in locking position and dotted lines representing them turned into unlocking position. Fig. 2 represents a side elevation of our complete device.

40 The reference-numeral 1 represents an ordinary box, and 2 the lid thereof, arranged and adapted to fit within it.

3 denotes a pair of transverse strips nailed across the opposite ends of the top of the lid.

45 4 represents a horizontally-disposed lever mounted on the pivot 5, rising perpendicularly from the plate 6. By "horizontally" is meant movable in the plane of the top of the lid. This plate is fastened to the top of the 50 lid by means of screws 7, having countersunk heads.

The lever 4, which forms one of the princi-

pal features of our invention, is provided with a pair of holes 4', located on the opposite sides of the pivot and out of alinement with 55 a line drawn through the longitudinal center of the lever.

9 represent the locking-rods, having their outer extremities pointed and passing through guide-holes 10 in the strips 3 on the top of 60 the lid, so that they will engage the inside walls of the box. The ends 9 of the rods are hook-shaped to hook into the holes 4' of the lever, whereby the rods can be attached and detached by simply hooking and unhooking 65 them without other preparation. The opposite extremities of the lever 4 are provided with longitudinally-extending trunnions 11 for the reception of loops 12 on the manipulating bail or handle 13. This handle is made 70 of a single piece of wire having sufficient resiliency to enable its looped ends to spread apart far enough to be removed from or attached to the trunnions 11. Shoulders 14 opposite the holes 4' are formed on each end of 75 the lever for the purpose of locking it against the sides of the hooked ends of the rods 9 when the opposite ends of the lever have passed the dead-center into locking position. The construction of the handle allows it to swing 80 laterally on the lever and fold down on the lid out of the way when not in use and to be lifted up into position for turning the lever, the combined handle, lever, and stud being substantially like a swivel.

85 Thus constructed it will be seen that when the lever 4 is turned at substantially right angles to the locking-rods, as seen in dotted lines, the rods will be withdrawn from engagement with the box and allow the lid to 90 be lifted out, and when it is desired to apply and lock the lid the latter can be dropped down into the box the required distance and the handle 13 given a turn from left to right, thereby spreading the arms away from each 95 other and moving them in an endwise direction to make their points enter the opposite ends of the box. By continuing to turn the lever around to the limit of its locking position one or both lugs of the handle will be 100 brought in contact with the side or sides of the locking-rods simultaneously with the passage of the hooked ends past the dead-center in relation to each other and the pivot, so

that there will be a tendency, caused by the back pressure of the rods, to hold the lever in its locked position to hold the cover in place.

Having thus described our invention, what we claim as new, and desire to secure by Letters Patent, is—

1. The herein-described locking device for box-lids, said device consisting in the combination of a centrally-pivoted, horizontal lever having a vertical axis and provided with holes, a pair of longitudinally-movable locking-rods secured in the holes and out of alignment with each other, a pair of lugs projecting from the opposite extremities of the lever, and a handle secured to said lugs and adapted to fall down on the top of the lid, substantially as described.

2. In a box-lid fastener, the combination with a lid, of a stud or fulcrum centrally disposed thereon and projecting upwardly therefrom, a horizontally-movable locking-lever having trunnions on its opposite ends and

provided with abutting shoulders, a bail having loops fitted over and pivoted on the trunnions so as to swing up and down, and a pair of rods pivotally attached to the lever at points between the axis and free ends, the contiguous ends of the rods being arranged to come in contact with the abutting shoulders on the lever when the latter is turned into locking adjustment, substantially as described.

3. The combination with a lid, of the locking-rods 9, the perpendicular stud or pivot 5 on the lid, the lever 4 parallel with the face 35 of the lid and the U-shaped handle 13 hinged on the lever, substantially as described.

In witness whereof we affix our signatures in presence of two witnesses.

HENRY M. SHEER.
SANFORD C. PITNEY.
